SUGAR CONTAINER WITH MEASURING AND DISPENSING SPOUT

Rosewell G. Capron, 5702 Lawndale,
Mesa, Ariz. 85205

Filed Feb. 19, 1974, Ser. No. 443,675

Term of patent 14 years

Int. Cl. D7—06

U.S. Cl. D7—17

FIG. 1

FIG. 2

FIG. 3

FIG. 1 is a top front perspective view of a sugar container with measuring and dispensing spout showing my new design;

FIG. 2 is a bottom rear perspective view thereof;

FIG. 3 is an exploded top front perspective view thereof with the spout cover in a partially open condition; and

FIG. 4 is an exploded side elevational view thereof partly in section as seen from the left of FIG. 3.

I claim:

The ornamental design for a sugar container with measuring and dispensing spout, as shown and described.

FIG. 4
